UNITED STATES PATENT OFFICE.

ANDREW RADEEFF, OF NEW YORK, N. Y.

PERFUMER FOR ELECTRIC FANS.

Application filed April 7, 1926. Serial No. 100,373.

The main object of this invention is to provide an attachment for electric fans which aids in scenting the atmosphere with perfume. The device comprises a plurality 5 of open mesh-covered containers upon a frame which are fastened in front of the propeller of an electric fan to exude perfumed fumes.

Another object is to provide a modified 10 type of device in which the perfume containers are fed from a supply bag.

The above and other objects will become apparent in the description below, in which characters of reference refer to like-named 15 parts in the drawing.

Referring briefly to the drawing, Figure 1 is a front elevational view of the preferred type of perfumer.

Figure 2 is a side elevational view of the 20 perfumer, showing it as mounted on the frame of an electric fan.

Figure 3 is an end elevational view of the preferred type of perfumer.

Figure 4 is a front elevational view of the 25 modified type of perfumer.

Figure 5 is a side elevational view of Figure 4.

Referring in detail to the drawing, the 30 numeral 10 indicates the circular ring composed of wire or some other rigid material. This ring has a plurality of containers 11, 12, 13, and 14, attached thereto. Said containers are provided with a bottom, are filled 35 with gauze saturated with perfume, are open at the top, and are covered by a wire mesh 15. A pair of rods 16 and 17 extend vertically and are affixed to opposing sides of the ring 10. Intermediate the length of these rods, pairs of clamp members 18 and 19 are 40 pivoted on said rods, as illustrated in Figure 3 and the free ends are normally retained in separated relation by springs 20 which are mounted between the cooperating clamp members.

45 In the modified type of device, a ring 21, similar to the ring 10 of the preferred type is used. The rods 22 and 23 extend diametrically across a ring 21 and project beyond the upper edge of the ring illustrated in Figure 4. In the modified type of device, a pair 50 of gauze containers 24 and 25 are used and are mounted on opposite sides of the ring.

These containers are similar in structure and design to that of the preferred form and are fed with perfume through tubes 26 and 55 27 which communicate with and continue from a rubber bag 28 which is closed by a filling cap 29 at its upper end. The modified form of device is provided with the clips 18 and 19 shown in the preferred form and 60 the same numerals will be used to indicate these parts.

The cage 30 of an electric fan which encloses the blades of the propeller usually 65 consists of two rings connected by tie rods 39 and the outer ring having a wire mesh to serve as a guard for preventing injury. To the outer ring 32, the device is attached. The motor 33 of the fan mounted upon the neck 34 of a base 35 actuates the fan in the 70 cage of the device and circulates a current of air past the containers. This air in enveloping the containers 11, 12, 13, and 14, causes circulation of this perfumed air to distant parts of the room. In the preferred 75 type of device, the gauze in the containers must be manually saturated, but in the modified type, the gauze is automatically saturated thru the tubes 26 from the reservoir bag 28.

80 It is to be noted that certain changes in form and construction may be made without departing from the spirit and scope of the invention.

I claim:

85 1. A device of the class described comprising a ring adapted to be attached to the cage of an electric fan, containers mounted on said ring and adapted to use perfumed gauze, said containers being mounted in front 90 of said fan, clamp members forming part of said ring, said clamps being adapted to engage the cage of the electric fan to secure the ring in front of the cage, bars extending diametrically between opposite sides of the 95 ring, said bars having the clamp members pivoted thereon, and springs normally closing said clamp members.

100 2. A device of the class described comprising a ring adapted to be attached to the cage of an electric fan, containers mounted on said ring and adapted to use perfumed gauze, said containers being mounted in front of said fan, clamp members forming

part of said ring, said clamps being adapted to engage the cage of the electric fan to secure the ring in front of the cage, bars extending diametrically between opposite sides of the ring, said bars having the clamp members pivoted thereon, springs normally closing said clamp members, a res-

ervoir bag mounted on said bars, and tubes leading from said bag into the containers, said containers being covered by a wire 10 mesh screen.

In testimony whereof I affix my signature.

ANDREW RADEEFF.
